(57) **CLAIM**

I claim the ornamental design for a display table, as shown and described.

DESCRIPTION

FIG. 1 is a perspective view of a first embodiment of a display table;

FIG. 2 is a front side elevation view thereof;

FIG. 3 is a rear side elevation view thereof;

FIG. 4 is a left side elevation view thereof, the right side elevation view being a mirror image thereof;

FIG. 5 is a top view thereof;

FIG. 6 is a perspective view of a second embodiment of a display table;

FIG. 7 is a front side elevation view thereof;

FIG. 8 is a rear side elevation view thereof;

FIG. 9 is a left side elevation view thereof, the right side elevation view being a mirror image thereof; and,

FIG. 10 is a top view thereof.

The broken lines shown in the drawings are for the purpose of illustrating portions of the display table and form no part of the claimed design.
